COMBINED MEMO PAD AND PEN HOLDER

Chuzo Mori, Tokyo, Japan, assignor to Carl Manufacturing Company Ltd., Tokyo, Japan

Filed Nov. 29, 1972, Ser. No. 310,280

Term of patent 14 years

Int. Cl. D19—02

U.S. Cl. D19—78

FIG. 5.

FIG. 2.

FIG. 1.

FIG. 3.

FIG. 4.

FIG. 1 is a front elevational view of a combined memo pad and pen holder showing my new design;
FIG. 2 is a top plan view;
FIG. 3 is a bottom plan view;
FIG. 4 is a left side elevational view; and
FIG. 5 is a right side elevational view.

I claim:

The ornamental design for a combined memo pad and pen holder, substantially as shown.
